JOINT CONSTRUCTION

Martin De Lin, Holland, Mich., assignor to Holland Furnace Company, Holland, Mich., a corporation of Michigan

Application July 21, 1937, Serial No. 154,700

1 Claim. (Cl. 285—25)

This invention relates to joint constructions, and more particularly to a joint construction adapted to be utilized for securing a cast metal cylinder to a sheet metal cylinder. The invention finds especial use in connecting a sheet metal stove pipe to the cast metal flue outlet of a combustion chamber for furnaces.

In furnace constructions it is common practice to connect sheet metal stove pipe to the cast metal outlet collar of the combustion chamber by fitting a crimped end of the sheet metal cylinder over the cast metal collar. Such joints are unsatisfactory because of the different coefficients of expansion of the two cylinders, and because a sudden increase in pressure within the combustion chamber may blow the sheet metal pipe loose from the cast metal collar. This disadvantage is not entirely overcome by bolting or otherwise securing the sheet metal pipe to the cast metal collar, because relative movement occurs between the two parts and permits leakages around the joint.

The present invention accordingly has for its primary object the provision of a joint construction for cast metal and sheet metal cylinders which is not subject to the disadvantages mentioned above. This object is attained, in part, by forming the cast metal cylinder with a radial face at one end thereof, providing the sheet metal cylinder with a radial flange, and by encircling the sheet metal cylinder with a cast metal sleeve having a radial flange which is bolted directly to the radial face of the cast metal sleeve whereby the radial flange of the sheet metal cylinder is securely locked between the cast metal cylinder and the radial flange of the cast metal sleeve.

The joint thus formed is made leak proof by providing an annular groove in the radial face of the cast metal member which is filled with compressible packing material. The radial flange of the sheet metal cylinder is pressed firmly against the packing material in the groove by the cast metal sleeve. The packing material thus effectively seals the joint between the two cylinders.

For a better understanding of the invention reference should now be had to the accompanying drawing, wherein—

Figure 1 is a perspective view of a furnace construction showing a sheet metal pipe secured to the cast metal collar of a combustion chamber in accordance with the present invention;

Figure 2 is a sectional view through the joint between the cast metal collar and the sheet metal pipe taken on substantially the line 2—2 of Figure 1; and

Figure 3 is an exploded view of the joint illustrated in Figure 2.

The furnace 10 shown in Figure 1 is a conventional construction including a cast metal outlet flue or collar 11 formed integrally with the combustion chamber, not shown. A sheet metal stove pipe or exhaust pipe 12, adapted to be connected to a chimney in a conventional manner, is shown secured to the cast metal collar 11.

The cast metal collar 11 is formed with a radial face 13 at its outer end and has an axially extending flange 14 at the inner periphery of said radial face 13. The radial face 13 is provided with an axially extending annular groove 15 adjacent the base of the axial flange 14.

The sheet metal cylinder 12 is of an internal diameter only sufficiently greater than the external diameter of the axial flange 14 to permit the sheet metal cylinder to be mounted on the flange as shown in Figure 2. The cylinder 12 is provided with a relatively short radially extending flange 16 at the end thereof. The radial extent of flange 16 is less than the radial extent of groove 15 so that the flange is located within the radial confines of the groove.

A cast metal sleeve 17 of an internal diameter substantially the same as the external diameter of the sheet metal cylinder 12 is mounted upon the cylinder 12. Cast metal sleeve 17 has a radial flange 18 at the end thereof which is of a radial extent locating its periphery in alignment with the outer periphery of the radial face 13 of cast metal cylinder 11.

A plurality of threaded recesses 19 are provided in the radial face 13 of the cast metal cylinder 19 adjacent the outer periphery thereof. Flange 18 of cast metal sleeve 17 is provided with a corresponding number of openings 20 adapted to be arranged in alignment with the openings 19. Cap screws 21 are provided for each of the cooperating openings 19 and 20 by means of which the radial flange 18 of cast metal sleeve 17 is connected to the radial face 13 of the cast metal cylinder with the radial flange 16 of the sheet metal cylinder 12 positioned therebetween. Preferably the radial face 13 and the radial flange 18 are formed with corresponding boss portions at their peripheries in which the openings 19 and 20, respectively, are located, as shown in Figure 1.

In assembling the parts thus far described, the annular groove 15 of cast metal cylinder 11 is partially filled with adhesive material, such as furnace cement 22, or the like. A fibrous ring or rope 23, such as asbestos or the like, is then placed in the groove 15 on top of the cement 22. There-

after, the outer surface of the fibrous ring 23 is also covered with the same adhesive material.

When the cast metal sleeve 17 is secured to the cast metal cylinder 11 by threading home the cap screws 21, the adhesive material 22 and the fibrous ring 23 are distorted as shown in Figure 2, completely filling all of the unoccupied portion of the groove 15, and also all of the unoccupied space between the inner surface of cylinder 12 and the outer surface of axial flange 14. Thus, a very tight joint is formed between the cast metal cylinder 11 and the sheet metal cylinder 12. It will be noted that the cap screws 21 are located radially outwardly of the periphery of the flange 16 at the end of the cylinder 12, so that the sheet metal cylinder 12 is secured to the cast metal cylinder 11 solely by reason of the sheet metal flange 16 being pressed between the packing material contained in groove 15 and the radial flange 18 of cast metal sleeve 17.

While the present invention has been herein shown and described as embodied in a joint for connecting a sheet metal stove pipe to the cast metal collar of a combustion chamber for a furnace, it will be readily understood that it may be embodied in various other forms of devices without departing from the spirit or scope of the appended claim.

I claim:

A joint construction comprising: a tubular member having a radial flange at one end thereof, an axially extending flange at the inner periphery of said radial flange, and an axially extending annular groove formed in the radial flange adjacent the base of said radial flange; a second tubular member having an end portion encircling the axial flange of the first member; said second member having a radial flange of less radial extent than said annular groove and located wholly within the radial confines of said annular groove; a sleeve surrounding said second tubular member and having a radial flange contacting the radial flange of the second tubular member and the radial flange of the first tubular member; the groove in the first tubular member being filled with flexible sealing material; and means for securing the radial flange of the sleeve to the radial flange of the first mentioned tubular member radially outwardly of the periphery of the flange at the end of the second tubular member, the construction and arrangement being such that when the sleeve is secured to said radial flange of the first-mentioned tubular member the flange of the second tubular member will be embedded in said sealing material.

MARTIN DE LIN.
